(57) **CLAIM**

I claim the ornamental design for a figure skate guard, as shown and described.

DESCRIPTION

FIG. 1 is a first side elevational view of a figure skate guard showing my new design, the opposite side elevational view being the mirror image to that shown; FIG. 2 is a bottom plan view thereof; FIG. 3 is a first end elevational view thereof; FIG. 4 is a second end elevational view thereof; FIG. 5 is a top view of the figure skate guard shown in FIG. 1; and, FIG. 6 is a top, side and front elevational view of the figure skate guard shown in FIG. 1. The broken line showing of the figure skate is for illustration purposes only and forms no part of the claimed design.
